Primary Examiner — Cathron C. Brooks*Assistant Examiner* — Kevin Rudzinski(74) *Attorney, Agent, or Firm* — Hasse & Nesbitt LLC; Daniel F. Nesbitt(57) **CLAIM**

We claim the ornamental design for a lighting fixture, as shown and described.

DESCRIPTION

FIG. 1 shows a bottom perspective view of the lighting fixture of the invention.

FIG. 2 shows a bottom view of the lighting fixture of FIG. 1.

FIG. 3 shows a top view of the lighting fixture of FIG. 1.

FIG. 4 shows a front elevation view of the lighting fixture of FIG. 1, where the rear elevation view is identical thereto; and,

FIG. 5 shows a right side elevation view of the lighting fixture of FIG. 1, where the left side elevation view is identical thereto.

The broken lines in the drawings illustrate unclaimed portions of the lighting fixture and form no part of the claimed design.
